(57) **CLAIM**

The ornamental design for a wrist watch case with band, as shown and described.

DESCRIPTION

FIG. 1 is a perspective view thereof,
FIG. 2 is a front elevational view thereof,
FIG. 3 is a rear elevational view thereof,
FIG. 4 is a top plan view thereof,
FIG. 5 is a bottom plan view thereof,
FIG. 6 is a left side elevational view; and,
FIG. 7 is a right side elevational view thereof.

The broken lines in the drawings are used to show portions of the watch band that do not form part of the claimed design.
